(57) **CLAIM**

The ornamental design for a pneumatic tire, as shown and described.

DESCRIPTION

FIG. 1 is a perspective view of a first embodiment of a pneumatic tire showing our new design;

FIG. 2 is a front view of the ornamental design of the pneumatic tire shown in FIG. 1, with a top plan view and bottom plan view of the pneumatic tire appearing the same as the front view;

FIG. 3 is a rear view of the ornamental design of the pneumatic tire shown in FIG. 1;

FIG. 4 is a right side view of the ornamental design of the pneumatic tire shown in FIG. 1;

FIG. 5 is a left side view of the ornamental design of the pneumatic tire shown in FIG. 1;

FIG. 6 is partial front view of the ornamental design of the pneumatic tire shown in FIG. 1, showing an enlargement of the portion 6-6 in FIG. 2;

FIG. 7 is a cross-sectional view of the ornamental design of the pneumatic tire of FIG. 1 taken along line 7-7 in FIG. 6;

FIG. 8 is a perspective view of a second embodiment of a pneumatic tire showing our new design; and,

FIG. 9 is a front view of the pneumatic tire shown in FIG. 8, the rear view, with a top plan view and bottom plan view appearing the same as the front view.
